UNITED STATES PATENT OFFICE

136,763

DESIGN FOR A COMBINED SPOOL HOLDER, THIMBLE, AND SCISSORS

Emanuel R. Morando, New York, N. Y.

Application July 17, 1943, Serial No. 110,679

Term of patent 7 years

To all whom it may concern:

Be it known that I, Emanuel R. Morando, a citizen of the United States of America, residing at New York, in the county of New York, State of New York, have invented a new, original, and ornamental Design for a Combined Spool Holder, Thimble, and Scissors, of which the following is a specification, reference being made to the accompanying drawing, forming a part thereof, in which:

Figure 1 is a side elevational view of a combined spool holder, thimble and scissors showing my new design.

Figure 2 is a similar view thereof with the thimble removed.

Figure 3 is a cross-sectional view thereof on line 3—3 of Figure 1.

Figure 4 is an end elevational view thereof with the thimble removed.

The dominant features of my design are shown in solid lines on the drawing.

I claim:

The ornamental design for a combined spool holder, thimble, and scissors, as shown and described.

EMANUEL R. MORANDO.
